UNITED STATES PATENT OFFICE.

JESSE D. LANGDON, OF WATERVILLE, WASHINGTON, ASSIGNOR TO THE AUXILIARY COOLER COMPANY, A CORPORATION OF WASHINGTON.

CUSHIONED VALVE-TAPPET.

1,241,745.

Specification of Letters Patent.

Patented Oct. 2, 1917.

Application filed November 2, 1916. Serial No. 129,111.

To all whom it may concern:

Be it known that I, JESSE D. LANGDON, a citizen of the United States, residing at Waterville, in the county of Douglas and State of Washington, have invented certain new and useful Improvements in Cushioned Valve-Tappets; and I do hereby declare the following to be a full, clear, and exact description of the invention, such as will enable others skilled in the art to which it appertains to make and use the same.

This invention relates to the class of valve actuating mechanisms, and more particularly to a cushioned valve tappet.

15 The principal object of the invention is the provision of a tappet arm designed to be elastically interdisposed between the valve and the valve actuating mechanism.

Another object of the invention is to provide the combination with one of the valves and the cam shaft of an engine, of a tappet arm fulcrumed on and elastically positioned between the actuating cam and the valve, so as to provide continuous contact between the 25 valve and cam.

A further object of the invention is to provide a cushioned valve tappet that will be noiseless in its action and self adjusting so as to compensate for the wear of the valve 30 and the various relative parts of the device.

With these and other objects in view as will appear as the description proceeds, the invention comprises the various novel features of construction, combination and arrangement of parts as will be more fully described hereinafter and set forth with particularity in the appended claims.

Referring to the drawings,

Figure 1 is a vertical transverse sectional view of my improved cushioned valve tappet shown applied to a demountable cylinder head wherein an overhead valve is used.

Fig. 2 is a vertical transverse sectional view through an L head type of motor showing another way in which my improved cushioned valve tappet may be used.

Similar characters of reference are used to denote like parts throughout the accompanying drawings and the following description.

Referring more particularly to the drawings, the reference numeral 1 indicates an upper fragmentary portion of a demount-

able cylinder head which is provided with the usual water jacket 2 and intake or exhaust passage 3.

Disposed vertically through this cylinder head 1 is a vertical stem 4 which is provided at its lower end with a valve head 5 designed to seat against the valve seat 6 under the action of the valve spring 7 arranged upon the upper end of the valve stem. This valve spring 7 is of the usual construction and is held upon the valve stem through the medium of the usual spring cap 8 held in place by a valve stem pin or key 9 that is passed through a slot in the upper free end of the valve stem 4 and rests within the spring cap as clearly shown.

The upper free end of the valve stem, in this instance is shown to be rounded as indicated by the numeral 10 but I desire to have it understood that the valve stem may be made flat upon its upper end or of any other desired construction. Resting upon this upper end of the valve stem is one end of a tappet arm 11 which in this instance is provided on its under face with an enlargement or boss 12 that is provided with a countersunk or depression 13 designed to receive the upper end 10 of the valve stem.

As shown this tappet arm 11 is positioned between the valve stem 4 and the actuating cam 14 mounted on the cam shaft 15 directly above the tappet arm. It is also to be noted that the tappet arm is disposed horizontally or substantially so between the valve stem and an actuating cam 14 and the opposite end thereof is provided with an elongated slot 16 for the reception of the upper end of a stud 17 that is threaded and connected with the cylinder head 1 as indicated by the numeral 18. This same end of the tappet arm is also provided on its under face with a depending circular flange 19 around which is positioned the upper end of a coil spring 20, the lower end of which rests upon an adjusting nut 21 upon the stud 17. By the provision of this adjusting nut, any desired tension may be placed upon the spring and when such tension has been produced, the adjusting nut may be held in adjusting position through the medium of the lock 22 arranged immediately below it.

In order to securely attach the stud with- 105 in the demountable cylinder head 1 I pro-

vide a clamping nut 23 that is arranged upon the lower end of the stud and is designed to be drawn down over a gasket 24 arranged beneath it so as to produce a perfectly tight joint between the stud and the cylinder head, and in cases where the stud is screwed through the water jacket, this gasket will serve to prevent leakage of the water through the connection of the stud with the cylinder head.

By this construction and arrangement just described, it will be apparent that the tappet arm is elastically cushioned between the valve stem and the actuating cam of the cam shaft so as to produce an absolutely noiseless action. It is also to be noted that by the arrangement and disposition of the various parts, that the actuating cam 14 will act as a fulcrum for the tappet arm, from which it will be seen that as the actuating cam revolves the tappet arm will be actuated to open the valve. Since the actuating cam revolves clockwise, it will be apparent that all lateral thrust upon the valve stem will be obviated by reason of the fact that the outer end of the slot 16 bears against the stud 17 as indicated by the numeral 25.

The tappet arm may be fulcrumed upon the actuating cam at any point intermediate its ends found most desirable, but in this instance it is shown fulcrumed adjacent the end that engages the valve stem and in view of this fact it will be obvious that the tension upon the spring 20 will be much weaker than that upon the spring 7 arranged on the valve stem 4, and that the nearer the actuating cam is moved into alinement with the valve stem, the less the tension will be upon the spring 20.

In Fig. 2 of the drawings will be seen another way in which my improved cushioned valve tappet may be used, which in this particular instance is used in connection with the L head type of motor. In this arrangement of the device, the stud 17 is disposed vertically within the crank case 26 and is threadedly connected at its upper end to the top portion 27 of the crank case as indicated by the numeral 28 and is held in attached position through the medium of a clamping nut 29 that is designed to bear against the end surface of the top portion 27 of the crank case.

The tappet arm 30 in this case is provided with an elongated slot 31 for the reception of the stud 17. As shown the opposite end of the tappet arm 30 is interdisposed between the lower end of the valve adjusting rod 32 of the actuating cam 33 mounted on the cam shaft 34 that is disposed longitudinally through the crank case 26.

The upper end of the valve adjusting rod 32 is provided with an adjusting nut 35 which is held in adjusted position through the medium of a lock nut 36. This adjusting

nut 35 is designed to engage the lower free end of the valve stem 4 when it is actuated through the medium of the cam 33.

The stud 17 in this instance is provided likewise with a cushioned spring 20 and an adjusting nut 36 mounted on the lower end of the stud 17 whereby any amount of tension may be placed upon the cushioned spring found desirable, such tension normally being just sufficient to hold and retain the tappet arm 30 in an operative position. As the cam 33 revolves it will move the inner end of the tappet arm 30 upwardly, which in turn operates to open the valve through the actuation of the valve adjusting rod 32, the outer end being supported and cushioned by the spring 20, said spring also serving to hold and maintain the tappet arm in continuous engagement with the cam and the valve adjusting rod.

It is also to be understood from the foregoing that by reason of the expansive force of the springs 20, that sufficient tension will be exerted on the ends of the tappet arms 11 and 30 to always maintain a continuous contact between the valve stem and the actuating cam, and by this continuous contact it will be apparent that all wear of the actuating cam and the other relative parts of the device will be compensated for by this elastic supporting means.

What I claim is:

1. The combination with a puppet valve, and valve actuating cam, of a tappet arm having one end interdisposed between and bearing against the puppet valve and the valve actuating cam, and elastic means for supporting the opposite end of the tappet arm.

2. The combination with a puppet valve, and a valve actuating cam, of an intermediary tappet arm, and variable tension means engaging the tappet arm and serving to hold the tappet arm in operative position between the puppet valve and actuating cam and maintain a continuous contact between said puppet valve, valve actuating cam and tappet arm.

3. In an engine, the combination with the cam shaft having a cam thereon, and a spring pressed valve thereof embodying a valve stem, of a tappet arm fulcrumed on and positioned between said cam and valve stem, and means for yieldingly connecting it to the engine, said connecting means serving to cushion the valve tappet arm between the cam and the valve stem.

4. In an internal combustion engine, the combination with the cam shaft having a cam thereon and a spring pressed valve therefor embodying a valve stem, of a cushioned valve tappet comprising a tappet arm having one end resting against the outer free end of said valve stem, and means yieldingly connecting the opposite end of said

5 tappet arm to the engine, said tappet arm adapted to be fulcrumed on the cam between its ends and cushioned between the cam, the valve stem and said yielding connecting means.

5. In an internal combustion engine, the combination with the cam shaft having a cam thereon, and a spring pressed valve thereof embodying a valve stem, of a cushioned 10 valve tappet comprising a tappet arm designed to have one end fulcrumed on and interdisposed between said cam and valve stem, and means for elastically connecting the opposite end of said tappet arm with the engine, said elastic connection serving to cushion the tappet arm between the cam and valve stem.

6. The combination with valve actuating mechanism and a puppet valve embodying a 20 valve stem, of a cushioned tappet arm having one end fulcrumed on and interdisposed between said valve actuating mechanism and valve stem, elastic tensioned means for supporting the opposite end of said tappet 25 arm and serving to hold and maintain said tappet arm in continuous contact with the valve actuating mechanism and the valve stem, and means for varying the tension of said supporting means.

30 7. The combination with valve actuating mechanism, and a puppet valve, of a tappet arm having one end fulcrumed on and interdisposed between said valve actuating mechanism and said valve, and means to elastically support the opposite end of said tappet arm, said elastic supporting means

adapted to exert a tension on the tappet arm to hold said tappet arm in continuous contact with said valve actuating mechanism and puppet valve, whereby wear between said parts will be automatically compensated for. 40

8. The combination with a puppet valve, and valve operating mechanism, of a lever fulcrumed on the valve mechanism and having one end elastically positioned between the puppet valve and the valve operating mechanism, and elastic supporting means for supporting the other end of the lever, said elastic supporting means serving as 50 the sole means of elastically supporting the lever in operative position between the puppet valve and the valve operating mechanism.

9. The combination with a puppet valve, and valve actuating mechanism, of a tappet arm interdisposed between the puppet valve and the valve actuating mechanism, resilient means engaging said tappet arm to yieldingly support it in position between the 55 puppet valve and the valve actuating mechanism, and additional means engaging the tappet arm to prevent lateral thrust of the tappet arm against the puppet valve. 60

In testimony whereof I have signed my 65 name to this specification in the presence of two subscribing witnesses.

JESSE D. LANGDON.
